STRIKING CASTING

Glenn F. Couch, Rochester, N. Y., assignor to
The Symington Company, New York, N. Y., a
corporation of Maryland

Application October 18, 1927. Serial No. 226,963

9 Claims. (Cl. 213—60)

This invention relates to combined striking castings for railway cars and more particularly to such adapted to receive replaceable carrier blocks.

The principal object of my invention, generally considered, is to provide a combined casting formed with portions serving, respectively, as a coupler stop or striking casting and a sill tie member or coupler carrier iron and provided with means for connecting said casting to the associated center sills of a car, said carrier iron portion being formed to hold a replaceable carrier block and wear plate.

An object of my invention is the provision of a combined striking casting and coupler carrier member suitable for use with a swivel butt coupler and adapted for supporting either a swing or interlocked coupler carrier.

Another object of my invention is to provide a combined striking casting and sill tie member adapted for receiving a carrier block with depending portions on the base thereof interlocking with the sill tie member and adapted for transverse insertion into place with respect thereto.

A further object of my invention is to provide a carrier block for supporting an associated coupler, which block is notched on its upper face to receive a removable wear plate.

A still further object of my invention is to provide a combined striking casting for use with railway cars which is adapted to receive a carrier block, the end portions of the base web of which are elevated above the remaining portion thereof and one of said portions is provided with an aperture adapted to register with a corresponding aperture in the supporting portion of the combined casting and receive a securing pin.

An additional object of my invention is to provide a combined casting adapted for connection with the center sills of a car and provided with a sill tie portion adapted to support a coupler carrier block, the side portions of said casting being apertured for permitting transverse insertion and removal of said block and the upper portion of said block being provided with bosses lying adjacent its ends and between which a wear plate is receivable, the upper ends of said bosses extending close to the top of the block, receiving apertures in the casting for limiting upward movement thereof.

Other objects and advantages of the invention relating to the particular arrangement and construction of the various parts will become apparent as the description proceeds.

Referring to the drawing illustrating my inven-

tion, the scope whereof is defined by the appended claims:—

Figure 1 is an end elevation, partly in transverse section, illustrating an embodiment of my combined striking casting with associated carrier block supporting the coupler; and

Fig. 2 is a central longitudinal sectional view of the construction shown in Fig. 1, the associated coupler being shown diagrammatically.

Referring to the drawing in detail, like parts being designated by like reference characters, there is shown a combined casting 1 formed with a coupler striking portion 2, a coupler carrier iron or sill tie portion 3, and rearwardly extending ear or web portions 4 preferably lying on the outside of and adjacent to the web portions 5 of the center sill 6 of the car. The web portions 4 are preferably connected to the adjacent ends of the center or draft sills 6 by a plurality of rivets 7 and are also preferably bifurcated or formed as upper and lower sections 8 and 9, respectively, leaving notches 10 therebetween, said notches partially embracing the slots 11 provided in the associated center sills 6 for the reception of the usual form of draft key 12. For strengthening the webs of the sills around said slots 11, cheek plates 13 are provided connected to said webs by rivets 14, some of which may also serve for connecting the combined casting to said sills. The rearwardly extending web portions 4 may also be provided with outstanding lug portions or flanges 15 adapted for connection with the reinforcing angle irons 16.

The striking casting portion 2 of the combined casting 1 is preferably formed with upright web portion 17 adapted for engaging with the horn of the coupler 18 illustrated diagrammatically by dot and dash lines upon sufficient rearward movement thereof and a lower inwardly extending web portion 19 overlying the shank of the coupler 18.

Extending from the upper edge of the web portion 17 and continued rearwardly to the end sill 20 is a shelf or web portion 21 which is preferably provided at its rear edge with an upstanding flange 22 connected to the web of the end sill 20 by means of rivets 23. The web 21 and flange 22 are preferably reinforced by triangular gussets 24, the end sill 20 being connected to the cover plate 25 and a flange 26 on the combined striking casting by rivets 27.

For bracing the web portions 17, 19 and 21 together longitudinally extending web portions 26 are preferably provided, said portions being cut away as illustrated to receive the front ends of

110

the upper flanges of the center sill 6 and the front edge of the cover plate 25. The rear edge of the web 19 is preferably reinforced by an upstanding bead or rib 28.

5 The coupler carrier iron or sill tie portion 3 of the combined casting is preferably formed with a substantially horizontal web portion 29 and upright flanges 30 positioned on opposite sides of said web, said flanges extending both 10 above and below said web and thereby providing a trough 31 in which is received the associated carrier block 32. Said carrier block 32 is inserted in and removed from place through one of the transverse apertures 33 provided in the web portions 4 of the casting and after insertion is prevented from loss or undesired removal by having 15 depending portions 34 on the base thereof which interlock between elevated end portions 35 of the web 29 of the carrier iron portion.

20 For locking the carrier block in place an upwardly offset end portion 36 on the base of the carrier block 32 is apertured, as indicated at 37, which aperture registers with a corresponding aperture 38 in the elevated portion 35 of the carrier iron portion, said apertures being adapted 25 to receive a pin 39 headed at its upper end and provided with an aperture 40 adjacent its lower end to receive a cotter or other locking device.

30 In order to lighten the weight of the carrier block 32, the central portion thereof is reduced in height by elevating the lower outline thereof as indicated at 41 and thereby omitting the base web 34 except adjacent the ends thereof. The supporting web 29 in the combined casting may 35 be depressed or downwardly offset along a corresponding distance as indicated at 42.

40 The flanges or webs 30 are preferably rigidified with respect to the web 29 by means of substantially triangular web or gusset portions 43 and at their ends the webs 30 are preferably curved outwardly and upwardly to merge with the side webs 44 of the casting which in turn adjacent their upper ends merge with the web 17 forming the striking portion of the casting.

45 Between the webs 44 are preferably positioned the bearing portions 45 which may be employed for supporting swing carriers for the coupler. In the present instance, however, such swing carriers are not used and the lower webs 46 of said 50 bearing portions 45 define the upper walls of the apertures 33 through which the carrier block 32 is received.

55 The carrier block 32 is preferably generally box-shaped in cross section with lower webs 34-36, side webs 47 and the upper web 48. The intermediate or central portion of said upper web 48 is depressed or downwardly notched as indicated at 49 between bosses 50, the upper edges of which extend close to the webs 46 and thereby 60 limit upward movement thereof in the apertures 33. The ends of the carrier block beyond the bosses 50 may be of reduced height as illustrated thereby saving in the weight of the block. The depressed portion 49 between the bosses 50 serves 65 for receiving and supporting a wear plate 51, which preferably is inverted U-shaped in cross section and involves an upper web portion 52 and depending flanges 53 on the sides thereof.

70 In the present embodiment I have shown a swivel butt coupler 18 associated with my combined casting 1 and the butt 54 of said coupler is relatively deep and the dimensions of the combined casting are such that said butt is insertable through the aperture 55 in said casting as illustrated at 56 by dot and dash lines in Fig. 1 only

when the carrier block 32 is removed. In order therefore to apply the coupler 18 it is necessary to first insert the butt 54 thereof through the aperture 55 in the combined casting 1 and raise the stem of said coupler to a position above that 80 illustrated in full lines in Fig. 1 whereupon the carrier block and its associated wear plate are insertable through the apertures 33 to the position illustrated. After insertion said block may be locked in position by means of the pin 39.

85 The ends of the sills 6 are notched as indicated at 57 to permit application of the combined casting but those portions of the webs 5 of said sills beneath said notched portions are continued outwardly into the aperture 55 in the combined casting to closely approach flanges or rib portions 58 on the combined casting which extend inwardly and are of sufficient size, and preferably correspondingly stepped to extend beyond the outline 90 of the web 5 and the securing rivets 59 and thereby protect both from injury through engagement of the coupler 18 therewith. Shortly below the level of the securing rivets 59 said flanges are preferably tapered and their depth decreased to approximately the thickness of the webs of the 100 center sills, as shown most clearly in Fig. 1. From there the flanges are continued a short distance and may terminate at approximately the level of the longitudinal center line of the coupler stem or slightly below the same.

105 From the foregoing disclosure it will be seen that I have devised a combined striking casting and coupler carrier iron which is suitable for receiving a swivel butt coupler and adapted for use with either a swing or an interlocked carrier. 110 The depending portions provided on the carrier block interlock the same with the coupler carrier or sill tie portion of the casing whereby the locking pin is merely necessary to prevent vertical movement of said block to unlocking position. 115 Even without the locking pin vertical movement of said block is limited to an amount which is just sufficient to permit removal thereof by the upstanding lugs 50 which approach the upper walls of the apertures 33 very closely. In order 120 to provide long life for said block the same is notched at its upper edge for receiving a renewable wear plate.

Having now described my invention, I claim:—

125 1. A combined casting comprising portions serving, respectively, as a striking casting and coupler carrier iron, said portions being connected by sides which are transversely apertured for receiving a carrier block, a carrier block inserted and supported on said carrier iron portion, the upper surface of said block being notched, and a wear plate, inverted U-shape in section, mounted on said block in said notched portion, and straddling a portion thereof, for supporting an associated coupler, portions of said block at the 130 ends of said notched portion extending to approximately the elevation of the upper surface of said wear plate.

135 2. A combined casting comprising portions serving, respectively, as a striking casting and coupler carrier iron, said carrier iron portion being formed with an upper web for supporting a carrier block, flanges lying on either side of said web providing a channel in which said block is seated, a carrier block seated on said upper web 140 in said channel, the upper portions of said block being formed with bosses defining a notched portion therebetween for receiving a wear plate, the ends of said block being received in corresponding apertures in said combined casting, and said 145

- bosses extending close to the top walls of said apertures for limiting relative movement of the block with respect to said combined casting.
3. A combined casting comprising portions serving, respectively, as a striking casting and coupler carrier iron, said carrier iron portion being connected to the striking casting portion by sides apertured for receiving an associated carrier block inserted endwise, said sides and carrier iron portion together with the striking casting portion defining an aperture for receiving the stem of an associated coupler, the sides defining said aperture being adapted for connection with associated car sills, and means on said sides for protecting the ends of said sills and the connecting means, said protecting means being formed as inwardly extending flanges of a depth substantially equivalent to the corresponding dimension of the connecting means adjacent said means and below the same decreasing in depth to substantially the thickness of the web of the center sill and finally merging into the sides of the combined casting.
4. A combined casting comprising portions serving, respectively, as a striking casting and coupler carrier iron, said carrier iron being connected to the striking casting portion by sides apertured for receiving an associated carrier block inserted endwise, said sides comprising spaced webs with bearing portions therebetween for supporting a swing carrier, the carrier iron portion of said casting being formed with upper webs for supporting said carrier block, said webs being disposed at a plurality of elevations, and a carrier block supported thereon and formed with base webs positioned at complementary elevations for interlocking with said carrier iron portion.
5. In combination with the center sills of a car having vertical webs and inwardly extending flanges, a combined casting comprising portions serving, respectively, as a striking casting and coupler carrier iron, said casting having rearwardly extending web portions lying outside of the webs of the center sills and connected thereto, the outer ends of said webs being notched to receive the striking casting portion of said combined casting, the remaining portions of said webs extending into a coupler receiving aperture in said casting and connected to the side walls thereof, the rearwardly extending webs of said combined casting being provided with outstanding flanges, and structural members connected to said center sills and flanges for rigidifying the connection therebetween.
6. In combination with U-shaped center sills, an end sill extending thereabove and connected thereto, angle irons reinforcing the lower edges of said center sills, a combined casting connected to said center sills, end sill and reinforcing angle irons, the ends of said center sills being notched for receiving the striking casting portion of said casting, the webs of said sills below said notched portions extending into a coupler receiving aperture in said combined casting and connected to the sides of said casting, the sides of said casting being apertured for receiving a coupler block inserted endwise and also formed with bearing portions for alternatively supporting a swing carrier.
7. A combined casting comprising portions serving, respectively, as a striking casting and coupler carrier iron connected by side portions, and provided with an aperture in a side portion for receiving an associated carrier block, said carrier iron portion being formed with a web portion adapted to support the carrier block after insertion through said aperture, the upper surfaces of end portions of said web portion being upwardly offset as compared with those of intermediate portions, and a carrier block with lower surfaces, portions of which are offset in a manner corresponding with said upper surfaces, seated on said upper surfaces of the web portions, with the portion engaging the intermediate web portion interlocked between the upwardly offset end portions.
8. A combined casting comprising portions serving, respectively, as a striking casting, with a vertical striking and a horizontal upper web, and coupler carrier iron, and provided with an aperture for receiving the stem of an associated coupler, the sides of the casting defining said aperture being adapted for connection with associated center sills, the upper outer corners of said sills being notched to receive the striking casting portion with the upper flanges of the sills supporting the upper web of the striking portion, the webs of said sills having extensions in the coupler aperture connected to the sides of said casting, and means on the sides of said casting protecting the ends of said sill webs and said connecting means from injury through swinging movement of the coupler, said protecting means being formed as inwardly extending flanges of a depth substantially equivalent to the corresponding dimension of the connecting means adjacent said means and below the same decreasing in depth to substantially the thickness of the web of the center sill and finally merging into the sides of the combined casting.
9. A combined casting comprising portions serving, respectively, as a striking casting and coupler carrier iron connected by side portions, one of said side portions having an aperture for receiving an associated carrier block, said carrier iron portion being formed with a web portion adapted to support the carrier block after insertion through said aperture, the upper surfaces of the end portions of said web portion being upwardly offset as compared with those of intermediate portions, a carrier block with lower surfaces, portions of which are offset like the carrier iron web portion, and seated on said upper surfaces of the web portions with the portion engaging the intermediate web portion interlocked between the upwardly offset end portions, one of said end portions with an upwardly offset surface and the registering portion of the block being provided with corresponding apertures, and securing means inserted in said apertures for locking said block to said casting.
